UNITED STATES PATENT OFFICE.

HAROLD JAMES HEDDERWICK, OF HILLHEAD, GLASGOW, SCOTLAND.

MEANS FOR LOCKING NUTS ON SCREW-BOLTS, SHAFTS, AND THE LIKE.

1,199,548.

Specification of Letters Patent. Patented Sept. 26, 1916.

Application filed January 12, 1914. Serial No. 811,571.

To all whom it may concern:

Be it known that I, HAROLD JAMES HEDDERWICK, a subject of the King of Great Britain and Ireland, residing at 3 Florentine Gardens, Hillhead, Glasgow, Scotland, have invented new and useful Improvements in and Relating to Means for Locking Nuts on Screw-Bolts, Shafts, and the like, of which the following is a specification.

This invention relates to improved means for positively locking nuts on screw bolts, shafts, and the like, hereinafter generally referred to as bolts, of the type of locking device which is applied to the nut after the nut has been screwed onto its bolt, or in other words, which is applied from the top of the nut.

For locking nuts on bolts, it has been proposed to provide a device adapted to be fitted on to the exterior of the nut, and when the nut is screwed home, deformed by being bent, so as to enter into locking engagement with the bolt, the device being released from locking engagement with the bolt, when required, by unbending the portion previously deformed. Devices of this character necessitate the use of special tools to produce the required bending and unbending, and the material of which the devices are made must necessarily be of a ductile or pliable character to permit the required bending to be effected.

According to this invention a locking device has side members, some or all of which act to prevent endwise dislodgment when the device is applied to a nut, and the side members of the device, or only the side members which act to prevent endwise dislodgment, or the device itself, are or is formed from metal, having sufficient inherent spring, so that when the device is applied, after the nut has been screwed home, the side members for preventing endwise dislodgment engage with the sides of the nut by springing into position. In all cases, each device is manufactured with all its parts ready for effecting their required engagements, and in no case is the engagement effected by deformation of the device after application. The device or portions thereof may be made non-rusting or non-corroding, or composed of metal having these qualities.

Locking devices constructed according to this invention are for use in conjunction with a nut of ordinary pattern, having any number of flat sides, the nut for the pur-

poses of the invention in some cases being modified by having a circumferential recess formed at its base, or in its sides, or with the equivalent thereof. A bolt for use in connection with this invention is formed with a slot extending transversely through the end of the bolt, and a locking device as constructed according to this invention has a bar formed as an undivided part with and extending transversely across the head of the device, adapted to enter into engagement with the slot, the head being formed to entirely surround the end of the bolt, associated with two or more side arms, which extend from the head, adapted to lie against and embrace opposite sides of the nut, each side arm covering or embracing a wide area of its respective side of the nut for the purpose of positively locking together the nut and bolt. A locking device for this purpose may be cut or stamped from sheet metal having a head part, formed to lie on the top of the nut and surround the end of the bolt, and having its bar formed as an undivided part therewith, adapted to enter into engagement with the slot formed in the end of the bolt, and from the rim of the head part, two or more side arms extend, each formed to cover or embrace a wide area, the arms being arranged so as to lie and bear against opposite, or several, sides of the nut, and act in conjunction with the bar to lock the nut against rotation. The lower part of each side arm, or of each of some of the side arms, is formed with a jaw to enter into engagement with a circumferential recess, or the equivalent thereof, on the nut, and hold the device against endwise dislodgment. To remove the locking device, the side arms, acting to prevent endwise dislodgment are sprung out of engagement, and the device is adapted to be quickly and completely removed, and the nut screwed off by an ordinary spanner in the usual manner.

As an alternative to forming a circumferential recess at the base of the nut an equivalent result may be obtained by providing a washer of appropriate diameter placed beneath the nut.

The device may be formed with side arms adapted to bear against all sides of the nut. The bar of the device may be disposed in any fixed angular direction relative to the side arms. The bend at the junction of the side arms with the head of the device may

be quick, for example, approximating to a right angle, or easier by increasing the radius so as to form a small loop or bow.

In the construction of devices, according to this invention, each of the side arms, which are required to have spring, must practically be free except at the junction of the side arm and the head part of the device.

10 Some examples of constructions according to this invention will now be described with reference to the accompanying drawings, in which:—

Figure 1 is a sectional elevation and Fig. 2 is a perspective view of the end of a bolt with nut and locking device applied. Fig. 3 is a side elevation and Fig. 4 is a plan of a nut with a modified form of locking device applied. Fig. 5 is a plan and Fig. 6 is a side elevation of a nut with a modified locking device applied. Fig. 7 is an inverted plan and Fig. 8 is a side elevation of a nut with a modified locking device applied. Fig. 9 is a side elevation and Fig. 10 is a plan 25 of a nut with a modified locking device applied. Fig. 11 is a sectional elevation, Fig. 12 is a side elevation, Fig. 13 is a plan, and Fig. 14 is a side elevation of the end of a bolt with nut and modified locking device applied. Fig. 15 is a plan and Fig. 16 is a side elevation of a nut and modified locking device applied. Fig. 17 is a side elevation, Fig. 18 is an end view and Fig. 19 is a sectional plan of a nut and modified locking 35 device applied. Fig. 20 is a side elevation and Fig. 21 is a part sectional plan of a nut and modified locking device applied. Fig. 22 is a side elevation and Fig. 23 is a part sectional plan of a nut and modified locking 40 device applied. Fig. 24 is a sectional elevation of the end of a bolt with nut and a modified locking device applied.

Referring to Figs. 1 and 2, the end of a bolt A is formed with a slot, A¹, extending 45 transversely through its end, and a nut B is formed at its base with a circumferential recess B¹, and the device, for locking the nut B upon the bolt A, consists of a head part C of approximately circular outline 50 which is adapted to surround the end of the bolt, A, associated with a bar D, formed as an undivided part of the head part, C, which is adapted to engage with the slot A¹ in the end of the bolt A. Extending from 55 the head part C there are side arms E, one only of which is seen, adapted to lie against opposite sides of the nut B, each of the side arms E being turned inward at its end to form a jaw E¹ for engagement with 60 the circumferential recess B¹. In this form of construction and in the others illustrated, each jaw is made about as long as the width of one of the flat sides of the nut. The bend at the junction of the side arms E 65 with the head part C is in this case ap-

proximately at a right angle. Each of the side arms E is beveled away on its inner side at E² to facilitate the entrance of an instrument for springing the side arms E out when the device is to be removed from 70 the nut B.

In some of the figures described, the side arms E are for clearness of illustration shown at a slight distance away from the sides of the nut B, but in practice they 75 would invariably be in surface contact therewith.

In Figs. 3 and 4, in addition to side arms E, for preventing endwise dislodgment of the locking device from the nut B when applied thereto, subsidiary side pieces E¹² are 80 provided to lie against sides of the nut B. D is the bar.

In the construction shown at Figs. 5 and 6 side arms E are provided and subsidiary 85 side pieces E¹² having curved edges are provided to lie against the sides of the nut B. D is the bar.

In the construction shown at Figs. 7 and 8 side arms E having jaws E¹ are provided 90 and additional side arms E¹³ are provided, each of the latter being free except at the junction with the head part C, and having a tendency by spring action to lie against the respective sides of the nut B. 95

Figs. 9 and 10 show a construction in which a downwardly extending rim E¹⁴ in the form of a continuous band is provided for encircling the top edge of the nut B to which the locking device is applied. In this 100 case the junction of each side arm E with the head part C is at the base of the rim E¹⁴. D is the bar.

In Figs. 11, 12, 13 and 14 a device is shown having an embossed inverted channeled bar D, the embossing being extended down the side arms E as shown at D³³. At the foot of each of the side arms E a pocket E²¹ is formed to receive the point of an instrument for use in springing the jaw E¹ out 110 of engagement with the recess B¹ of the nut B. In each side arm E an aperture is formed between the bottom of the embossed part, D³³, and the top of the pocket, E²¹.

In the construction shown at Figs. 15 and 16 tongues H, which are fixed against endwise movement relative to the device, are provided, and so arranged that by pressing the tongues H toward one another the side arms E may be released and the device 120 drawn out of locking engagement with the nut B. D is the bar.

In the construction shown at Figs. 17, 18 and 19 the device is furnished with a strap C³ to give greater strength and rigidity. 125 The strap C³ as shown is composed of thicker metal than the other parts of the device and lies beneath the head part C. The bar D consists of a portion of the strap and a bar connecting the side portions of the head part 130

C. The side arms E are provided with jaws E¹.

The construction shown at Figs. 20 and 21 comprises extensions E¹⁵ from the head part C which are bent down so as to overlap sides of the nut B, the ends of the extensions E¹⁵ being turned out to engage with the sides of an aperture in the side arms E.

The construction shown at Figs. 22 and 23 consists of a head part C having extensions E¹⁶ connected to the head by ties E¹⁷. The extensions E¹⁶ are arranged to almost encircle the nut B and have ends which are turned out to engage with apertures in the side arms E.

In the construction shown at Fig. 24 the bar D is arched in order to give greater travel to the nut B on the bolt A.

I claim:

1. A device for locking a nut against rotation on a bolt, the nut having flat sides, said device comprising a head part constituting an encircling portion adapted to surround the end of the bolt and lie upon the flat surface

of the top of the nut, a bar extending diametrically entirely across the aperture in the encircling portion and formed at each end as a part of the side of the encircling portion, said bar being provided for engagement with a slot extending transversely through the end of the bolt, side arms extending from the head part, the side arms being formed each to cover a wide surface area, two only of the side arms having each at its lower part a jaw about as long as the width of one of the flat sides of the nut, each of the two side arms being practically free except at the junction with the head part and having inherent spring permitting the jaws to be sprung into engagement when the device is applied from the top of the nut, and the two side arms arranged to lie against and embrace opposite sides of the nut, for the purposes set forth.

HAROLD JAMES HEDDERWICK.
